2 SHEETS—SHEET 2.

UNITED STATES PATENT OFFICE.

PETER M. KLING, OF LACONIA, NEW HAMPSHIRE.

POST FOR WINDOWS.

1,307,822.

Specification of Letters Patent. Patented June 24, 1919.

Application filed September 5, 1917. Serial No. 189,741.

To all whom it may concern:

Be it known that I, PETER M. KLING, a citizen of the United States, and residing in Laconia, in the county of Belknap and 5 State of New Hampshire, have invented certain new and useful Improvements in Posts for Windows, of which the following is a specification.

This invention relates to posts or other 10 structural members which are suitable for holding window sashes or other glass-holding frames and has for its primary object to provide an improved construction for rendering such posts or members light in 15 weight and economic to manufacture while at the same time adapting them to render the structure of which they constitute a part, more capable of resisting the shocks and strains to which it is subjected. An- 20 other object is to provide an improved window frame construction. Other and further objects will appear in the specification and be pointed out in the appended claims, ref- 25 erence being had to the accompanying drawings, which exemplify my invention in some preferred embodiments.

In the drawings,—

Figures 1, 2 and 3 are transverse sections of improved double T posts or structural 30 sections;

Fig. 4 is a perspective view of portions of a car body which embodies my invention;

Fig. 5 is a transverse section of a steel twin T post trimmed with wood for a com- 35 posite railway car;

Fig. 6 is a similar section of a steel twin T post trimmed with metal for a steel rail- 40 way car.

Referring more particularly to the draw- 45 ings, the structural section or beam shown in section in Fig. 1 is constructed of sheet metal provided with longitudinal folds 1 and 2 which extend longitudinally of and form the double thickness flanges 3 and 4.

In effect these flanges 3 and 4 may be consid- 50 ered as portions intermediate to a central longitudinal portion 5 and the parallelly disposed lateral edge portions 8, 8. Said flanges 3 and 4 are arranged in substantially 55 the same plane as the central longitudinal portion 5 and project normally in opposite directions from the lateral edge portions 8, 8, with which they are joined by bends 6 and 7. These parts are reproduced in the se- 60 veral figures hereinafter referred to. In the 65 embodiment shown in Fig. 2, the structural

section is similarly constructed, but in addition, a channel beam 9 is arranged with its flanges 10 presented outwardly and preferably spot-welded to the spaced parallel flanges 8, thus forming a closed channel extending longitudinally through the beam or post. According to Fig. 3, the sheet metal has been provided with additional bends 11 and 12 to bring the lateral edges of the flanges 13 and 14 into close abutment to form a flange weld at 15, thus forming a somewhat similar construction to that shown in Fig. 2 without employing the channel section 9. In Fig. 4 of the drawings, an 70 adaptation of my invention to a railway passenger car is shown and in which the side wall of the car comprises vertically extending posts, with their top plates or flanges 5 presented outwardly, which posts may be 75 constructed according to either of the Figs. 1, 2 or 3. In this embodiment of my invention, the spaced parallel flanges 17 have mounted thereon the angle irons 18 which are parallelly arranged to extend vertically 80 of the flanges 17. Mounted between the flanges 18 are window sashes 19, while between the flanges 18 and the plates 5 are mounted fixed sashes 20. In car construction, the strain on the vertically arranged 85 post or section, arises from longitudinal shocks caused by stopping, starting and collisions. According to the present invention, such posts are arranged to impart increased 90 rigidity to the side wall of the car which acts as a truss to absorb these shocks. As shown in Fig. 5, a furring strip 21 which may be constructed of wood for example, is interposed between the flanges 8 and provided with a finishing panel 22 which may 95 form a portion of the inner wall of the car. In Fig. 6, which shows a preferred adapta- 100 tion of my invention to a steel car, the channel beam 9 is secured to the flanges 8 of the post or structural section, by means of rivets 23, which also serve to secure to the flanges 8 a structural section comprising folds 24 and 25 with an inner panel 26 for the inner wall of the car. According to 105 Fig. 5, grooves 27 for a movable window sash may be provided between wooden strips 28 mounted on spaced flanges 8, while guiding grooves 29 for curtains may be provided between panel 22 and the adjacent strips 28. According to Fig. 6, angle beams 30 are arranged oppositely to flanges 31 to 110 form grooves 32 for the movable sashes, said

flanges 31 being provided on the inwardly presented structural sections which include the panels 26. Grooves 33 for curtains are formed between the folds 24 and 25 in this 5 embodiment. The advantages of my improved construction will now be readily understood and briefly described are as follows:

This construction may be simply and 10 economically made, and provides an effective post or structural section which may be used in cars, boats, or any other place where mounted sashes or other glass holding frames are required. This construction is 15 peculiarly serviceable in connection with such structures which are subjected to shocks, such as are produced in connection with railway cars as pointed out above. Such a construction when substituted for 20 the usual car construction, in which the furring strips are applied to single vertical flanges which project inwardly from the ordinary T-beams, affords much better support for the furring strips which, as shown 25 in Fig. 5, may be interposed between the spaced flanges 8. In this position, the furring strip reinforces the spaced flanges 8, thus improving the truss construction of the side wall of the car. This construction is 30 stronger and weighs less per linear foot than that usually employed for similar purposes. Furthermore, my improved section can be riveted to the side of a car with a single 35 row of rivets in the center, or by a double row of rivets when the sheets are spliced, whereas in the old construction, the single T section always requires two rows of rivets for a similar purpose. This construction may be used equally well for single or 40 double sash, or for sashes that are raised or dropped. Incidentally, the provision of a furring strip between the spaced flanges 8 facilitates the trimming of the car when compared to similar work according to the 45 old construction. Thus for example, it becomes much easier to provide for electric wiring, push buttons and sash guide arrangements when my improved section is used in such places as car windows. Furthermore, where a car post is employed, 50 there must be sash retainers. The outside

sash retainers should be solid with the post, a requirement which is fully met in my improved construction.

I claim:

1. The combination with a strip or beam, of a twin T section comprising a central longitudinal portion, laterally spaced longitudinal edge portions embracing opposite faces of said strip or beam, and longitudinal portions intermediate to said central longitudinal portion and said longitudinal edge portions respectively, said intermediate portions being folded longitudinally to form longitudinal reinforcements projecting oppositely from longitudinal edge portions respectively. 60

2. The combination with a furring strip, of a twin T section comprising a central longitudinal portion contacting with one 70 face of said strip, lateral longitudinal edge portions embracing other faces of said strip contiguous to the first mentioned face, and other longitudinal portions intermediate to said central and lateral edge portions, each 75 of said intermediate portions being closely folded longitudinally to constitute reinforcement longitudinal flanges of double thickness in substantially the plane of said central portion. 80

3. In a car window construction, a twin T section comprising a central longitudinal portion, parallel longitudinal edge portions arranged normally to said central longitudinal portion, and intermediate longitudinal 85 portions, each of said intermediate portions being close folded to provide flanged reinforcements arranged substantially in the plane of said central longitudinal portion and projecting oppositely from said parallel 90 edge portions.

4. The combination with the side wall of a car, of a twin T post extending vertically of said side wall and comprising a flat plate portion presented outwardly, spaced parallel flanges extending longitudinally of said post and presented inwardly from said flat plate portion and normally thereto, said flanges being spaced inwardly from the lateral edges of said flat plate portion. 95

PETER M. KLING.
